UNITED STATES PATENT OFFICE.

LEWIS T. WILCOX AND FRANCES W. WILCOX, OF PEEKSKILL, NEW YORK; SAID LEWIS T. WILCOX ASSIGNOR TO WILCOX PATENTS CORPORATION, OF PEEKSKILL, NEW YORK, A CORPORATION OF NEW YORK.

SHIRT.

Application filed June 29, 1922. Serial No. 571,724.

Our present invention relates to an improvement in shirts and more particularly to that type commonly known as a negligee shirt. In the use of shirts of this type, particularly when stiff turned down collars are worn, the upper portion of the front of the shirt wears more rapidly than any other portion of the garment, and in fact often times wears through so that the shirt has to be discarded before there is any appreciable wear in any other part of the shirt. We are aware that heretofore various attempts have been made to overcome this difficulty. For example, it has been proposed to employ a shirt in which there is provided a plurality of detachable and removable sections in the shirt front, but obviously this is not only cumbersome, but an impractical structure. We are also aware that heretofore it has been proposed to so construct a shirt that the front portions of the body may be removed and reversed so as to renew the worn portions at the upper portion of the shirt front adjacent the neck band. In this type of shirt, however, so far as we are aware, the removal and reversal of the parts of the shirt has necessitated the entire reconstruction of the shirt or practically so and to such an extent as to make the labor involved substantially equal to that in the construction of an entirely new shirt and the resultant cost is practically prohibitive. Of course, we are also aware that it is possible to so insert new front sections in the shirt body as to overcome this difficulty of the wear in the shirt front, but in so doing there is an obvious difference in the new material and that which composes the old portion of the garment.

The object of our invention is to overcome these difficulties and in so doing to provide a garment so constructed that the front sections of the shirt may be removed and shifted to position independently of the connections between the shirt body and sleeve, the shirt body and the yoke members or shoulder straps and the other connections between the shirt body and the neck band of the garment so that the removal and shifting of the front sections of the shirt to new positions is a relatively simple and inexpensive operation, thereby increasing the wear

and life of the shirt to at least double that of a shirt in which our improvements are not incorporated. The shirt made in accordance with our present invention will be hereinafter more particularly described in conjunction with the accompanying drawings, in which,

Fig. 1 is an elevation of a shirt made in accordance with our invention.

Fig. 2 is an enlarged section on line 2-2, Fig. 1.

Fig. 3 is an enlarged cross section on line 3-3, Fig. 1.

Fig. 4 is an enlarged cross section on line 4-4, Fig. 1.

Fig. 5 is a partial elevation of the front portion of the neck band.

Fig. 6 is an elevation illustrating the connections between the shirt front section, the collar band, the yoke and the sleeve member with the parts in a substantially flattened condition.

Fig. 7 is an elevation of a shirt front section of another construction, and

Fig. 8 is a partial elevation of a third shirt front construction.

Referring to the drawing and particularly to Figs. 1 to 6 inclusive, the shirt made in accordance with our invention comprises the usual body member of the shirt in which there are detachable and shiftable front sections indicated at A and C respectively. These front sections form portions of the front of the body of the shirt, each front section being completed by a front side section indicated at B for the left hand side of the shirt and D for the right hand side of the shirt. Also as is customary the shirt includes a collar band E, the yoke or shoulder straps F and sleeves G to which, respectively, are connected the cuffs indicated at H and I. As is customary one edge of the shirt front section C is provided with a series of buttons K and in corresponding positions the other shirt front section A is provided with a series of button holes K'.

In the construction of the shirt the front section C is connected to the side section D by a line of stitching indicated at 5°. Before these parts are thus connected the longitudinal edge of the shirt front section C is preferably folded over on itself and con-

neected by a line of stitching indicated at 2. Similarly the adjacent edge of the side section D is turned over and the folded portion is connected along a line of stitching 5 indicated at 1. Similarly in the other side of the garment the longitudinal edge of the front section A is turned over and the parts connected by a line of stitching 1' and the corresponding edge of the side section B turned over and the parts connected by a line of stitching 2'. These folded over edges of the sections A and B are then connected with the folded over section overlapping by a line of stitching indicated at 6². The sleeves G of the garment are connected to the side sections B and D and to the other portions of the body of the garment along lines of stitching indicated at f and f'. The yoke members F are preferably made of two plies of fabric with the ends thereof turned and connected by lines of stitching indicated respectively at 7 and 8 so as to leave a pocket between a portion of the forward edges of the members of the yoke for the reception of the upper edge or a portion of the upper edge of each of the front sections A and C. For example, a portion of the upper edge of the front section A is connected between the corresponding yoke members by a line of stitching indicated at 6', and similarly a portion of the upper edge of the front section C is connected between the members of the other yoke by a line of stitching indicated at 5'. In a similar manner, the neck band may be constructed of two plies of material and the forward ends thereof connected by a line of stitching indicated at 6³ so as to leave a pocket for the reception and connection of the curved portion of the upper edge of the front sections A and C. For example, the curved portion of the upper edge of the front section A is received in the pocket thus formed and in the corresponding end of the neck band and connected thereto by a line of stitching indicated at 6. In a similar manner the curved portion of the upper end of the front section C is received between the parts of the corresponding end of the neck band and connected thereto by a line of stitching indicated at 5. It will be understood from the foregoing description that the lines of stitching 5, 5' and 5² are one continuous line of stitching, and similarly the lines of stitching indicated at 6, 6' and 6² are substantially a continuous line of stitches.

The cuff members H and I may be made reversible as is described in a copending application Serial No. 571,725, filed June 29, 60 1922, and as herein indicated when turned to one position the lines of stitches 11 and 15 are visible, while when turned to the other position there is a line of stitches indicated at 13 that is visible.

35 It will now be apparent that by simply

ripping the stitches indicated at 5, 5' and 5² in one side of the shirt and those indicated at 6, 6' and 6² on the other side of the shirt, the shirt front sections A and C may be disconnected and shifted so as to remove any worn portions at the upper ends thereof adjacent the neck band and the parts reconnected by remaking these stitches without in any manner disturbing any other portion of the shirt construction.

By reference to Fig. 7, it will be seen that if desirable the upper end of the shirt front section C may be provided with an indicating or pattern mark designated by the lines 16 and 17 which serve as a pattern for cutting this section and also for marking and cutting the corresponding section, and furthermore that after the parts have been shifted once the front sections may be removed again and reversed, and for this purpose an indicating or pattern mark is made at the lower end of the removable front section as is indicated by the lines 16', 17'. It will also be apparent that the shirt front sections as indicated in Fig. 8 may be provided with pattern marks L and L' for use in determining the positions in which the material should be cut, and also by which, when the parts are reversed, the position of the buttons and button holes may be determined. In this figure of the drawing the dotted line indicated by M designates a hole which has been worn through the upper portion of the front section of a shirt.

We claim as our invention:

1. An open front negligee shirt having a body, neck-band, yoke and sleeves, and in each front portion thereof a member comprising a front section and a side section, the said side section being permanently connected to a part of the yoke, a portion of a sleeve and a portion of the body and extending forwardly of the axillar line of the garment, the said front section extending the entire length of the garment and connected at its rearward edge to the forward edge of the said side section by a line of stitching along which it is separable from the said side section so as to be shifted to a different longitudinal position and to be reconnected to the said side section by a similar line of stitching to eliminate a worn portion at the upper end thereof.

2. An open front negligee shirt having a body, neck-band, yoke and sleeves, and in each front portion thereof a member comprising a front section and a side section both extending the entire length of the garment, the said side section being permanently connected to a portion of the yoke, a portion of a sleeve and the body of the garment, and the front section being connected at its upper edge by lines of stitching to a portion of the neck-band, a portion of the yoke, and at its inner edge to the forward edge of the

said side section whereby without disturbing the connections between the side section and the yoke, sleeve and body of the garment the said front section is separable along the said 5 lines of stitching from the neck-band, yoke and side section to be shifted to another longitudinal position and to be re-connected by

other lines of stitching to the said neck-band, yoke and side section to remove an upper worn portion of the said front section. 10

Signed by us this 22nd day of June, 1922.

LEWIS T. WILCOX.

FRANCES W. WILCOX.
